UNITED STATES PATENT OFFICE.

OLAF O. MARTIN, OF PORTLAND, OREGON, ASSIGNOR TO ELLIOTT-FISHER COMPANY, OF HARRISBURG, PENNSYLVANIA, A CORPORATION OF DELAWARE.

PAPER SUPPORTING AND FEEDING MECHANISM FOR TYPE-WRITING MACHINES.

1,159,404.

Specification of Letters Patent.

Patented Nov. 9, 1915.

Application filed February 24, 1910. Serial No. 545,608.

To all whom it may concern:

Be it known that I, OLAF O. MARTIN, a citizen of the United States of America, residing at Portland, in the county of Multnomah and State of Oregon, have invented certain new and useful Improvements in Paper Supporting and Feeding Mechanism for Type-Writing Machines, of which the following is a specification.

10 This invention relates to improvements in typewriting machines, and more particularly to a paper supporting and feeding mechanism adapted for use in connection with a downwardly acting printing mechanism.

The object of the invention, stated generally, is to provide a downwardly printing typewriter with a supporting structure including a platen, and means for supporting, 20 guiding and feeding a continuous web of paper which is led around the platen into position to be printed upon to the end that the paper web or strip may be continuously printed upon without shifting the machine longitudinally of the paper for line spacing 25 as is usually necessary in this form of typewriter.

A further object of the invention is to provide retaining means for securing the machine in position for printing and operative to permit said machine to be moved back on the supporting structure to a position in rear of the platen when access to the latter is desired.

35 Further objects subordinate to those stated will appear as the succeeding description of the illustrated embodiment of the invention is developed.

In the accompanying drawings—Figure 1 is a perspective view of an Elliott-Fisher writing-adding machine equipped in accordance with my invention. Fig. 2 is a similar view of the machine supporting platen frame. Fig. 3 is a plan view of the subject-matter of Fig. 2. Fig. 4 is a detail sectional view on the line 4—4 of Fig. 3. Fig. 5 is a longitudinal sectional view through the platen frame and parts carried thereby. Fig. 6 is a perspective view of the platen frame and associated parts inverted, the paper roll being shown removed, but the normal position thereof being indicated in dotted lines. Fig. 7 is a detail sectional view showing one of the machine catches and

associated parts. Fig. 8 is an enlarged sectional view of the front end portion of the platen frame and associated parts, the active position of the paper feeding mechanism being shown in full lines and the inactive position of such mechanism being indicated in dotted lines. Fig. 9 is a section approximately on the line 9—9 of Fig. 3, the line space mechanism being shown in different positions in full and dotted lines. Fig. 10 is a sectional view approximately on the line 10—10 of Fig. 3 with the line spacing mechanism indicated in different positions and the variable stop of said mechanism set in a different position from that shown in Fig. 9. Fig. 11 is a view similar to Fig. 10 but showing still another adjustment of the variable stop. Fig. 12 is a detail view of the variable line space stop and immediately adjacent parts. Fig. 13 is a detail elevation of the mounting for the line space stop with parts broken away to more clearly show the detent for holding the stop in its adjusted position. Fig. 14 is a detail perspective view of the line space lever, and Fig. 15 is a similar view of the line space pawl carrier.

Each part wherever shown is indicated by its proper reference character.

The Elliott-Fisher writing-adding machine indicated as a whole by 1 and shown clearly in Fig. 1 of the drawings, is a typewriter of the downwardly printing type well known to commerce. This machine includes a main machine frame 2, supporting a carriage 3 which travels in the direction of letter spacing under the control of keys 4, the depression of which causes the operation of downwardly acting type arms 5 (indicated in Figs. 1 and 5) and also operates escape- 85 ment mechanism, not shown, which permits the carriage to be drawn step by step under 90 the impulse of spring drums 6 connected to the carriage by tapes 7. The numeral keys also effect the operation of a register or adding mechanism 8 supported in rear of the carriage 3 by the frame 2. Ordinarily in 100 this type of machine the main machine frame 2 is shifted longitudinally of the work sheet for line spacing. In the arrangement here shown the frame 2 is merely shiftable to and from its operative position, 105 but the line spacing of the printing is effected by a line space feed of the work sheet. The machine frame 2 is supported

upon what may be termed a platen frame 9, the upper edges of the side members 10 and 11 of which constitute tracks or guides upon which travel rollers 12 carried by the 5 frame 2 in front and rear, see Figs. 1 and 5.

In Fig. 1 the machine is shown moved back to a position in rear of its normal or operative position, but in Fig. 5 the machine is shown in its forward or printing 10 position where it is secured to the platen frame or supporting structure 9 by movable catches 13 pivoted to the frame 2 and adapted to engage notches 14 in the side members 10 and 11 of the frame 9, see Figs. 1 and 7. 15 The catches 13 are urged toward their engaging positions by springs 15 and include finger pieces 16 to facilitate the movement of the catches against the resistance of their springs. When it is desired to push the machine back from its printing position the operator merely grasps the frame 2 adjacent to its opposite ends and this act elevates the finger pieces 16 and thus releases the catches to permit the machine to be 20 moved back as desired. When the machine is again drawn forward the catches snap in place and the frame 2 is securely held in proper relation to the printing point of the platen during the printing operation. 25

In addition to the side members 10 and 30 11, the frame 9 includes a number of transverse members which serve to stiffen the supporting structure of the machine, for instance front and rear end bars 17 and 18 35 of cylindrical cross section, and a flat intermediate bar 19, as shown in Fig. 5. These transverse bars 17, 18 and 19 are secured by screws, as indicated in Fig. 6, and in addition thereto are other transverse members to 40 which reference will be made hereafter. The bar 17 is located at the lower front corner of the frame and in rear thereof is mounted a transversely disposed cylindrical platen 20 of suitable material provided with 45 a spindle 21 having bearings in the side members 10 and 11 of the frame and provided with terminal thumb wheels 22 to facilitate the free rotation of the platen in a manner well understood in the art.

Between one end of the platen and the 50 frame bar 11 a ratchet wheel ordinarily known as the line space ratchet 23 is fixed to the spindle 21 and is engaged by a detent 24 of usual construction, to prevent accidental movement of the platen during the 55 printing operation. Associated with the platen are front and rear feed rolls 25 and 26, the former being mounted in the upper ends of roll frames 27 mounted to swing 60 from a transverse rock shaft 28 and urged toward the platen by springs 29 secured to the transverse frame bar 17. The roll frames swing independently of each other, being urged by their individual springs to 65 present the rolls 25 against the paper web

z which is led under the platen from a point in rear thereof and is carried around and over the platen at the upper side of which the printing point or line of the machine is located.

The rear feed rolls 26 are mounted in roll frames 30 similar to the frames 27 and swing from a transverse rock shaft 31 located in rear of the platen. The frames 30 are urged toward the platen by springs 32 bearing upon the roll frames and secured to the under side of the intermediate frame bar 19. The front and rear rolls 25 and 26 are located at diametrically opposite points of the platen, the rolls 25 being located comparatively adjacent to but in front of the line of writing. In order to move the feed rolls away from the platen to inoperative positions (as indicated in dotted lines in Fig. 8) to facilitate the manipulation of the work sheet, I provide what may be termed a release lever 33 mounted to swing from the bar 17 adjacent to the long under side of the frame and having a short end 34 provided with a concavity 35 designed to coact with an arm 36 depending from the shaft 28, the arm being connected by means of a link 37 to a similar arm 38 depending from the shaft 31.

Extended from each of the shafts 28 and 31 are radially disposed pins 39 disposed to engage cross-bars 40 of the frames 27 and 30. Normally the feed rolls and their associated parts occupy the positions shown in full lines in Fig. 8. When, however, it is 100 desired to throw off the feed rolls the lever 33 is depressed to the dotted position in Fig. 8, the short end 34 of said lever engaging and swinging the arm 36. This in turn rocks the connected shafts 28 and 31 105 and causes the pins 39 extended therefrom to engage the bars 40 of the roll frames and urge said frames away from the platen against the resistance of the springs 29 and 32, the relation of the axes of movement of 110 the lever 33, the arm 36 and the coacting portions of the lever and arm being such that the parts will be retained in their inoperative positions until the lever 33 is again thrown up or returned to normal position. 115

The paper web z is led to the platen 20 from a paper roll 41 wound upon the spindle 42 supported by open bearings 43 in bearing plates 44 secured to the inner faces of the frame members 10 and 11 at points adjacent to the rear end of the frame, see Figs. 5 and 6. From the under side of the roll 41 the web z is led over a horizontal apron 45 of sheet metal or other suitable material secured at its rear edge to a transverse bar 46 and extended over the transverse frame bar 19. In advance of the bar 19 the apron 45 is led in a downward direction to a point adjacent to the periphery of the platen around which it is carried to a point ad- 125 130

5 jacent to the writing line, the platen and apron being suitably spaced to permit the interposition of the web. At points opposite the feed rolls the apron 45 is provided
 10 with openings 47 for the accommodation of the rolls and for convenience in manufacture this apron may be formed in several sections, that portion extending around the platen being secured in place by tabs 48
 15 screwed to the members 10 and 11. In order to facilitate the feeding of the front end of the web to the platen it is desirable to provide a paper guide 49, preferably of sheet metal, extending rearwardly from the
 20 platen and conforming to that portion of the apron 45 which extends from the bar 19 to the vicinity of the rear feed rolls. The rear end of the guide 49 is bent upwardly, as indicated at 50, to provide a flared end
 25 to the guideway 51 defined between the guide 49 and the apron 45. Thus when the rear end of the paper web is drawn over the apron 45 from the roll it is readily passed into the guideway 51 and led thereby to the
 30 platen around the front side of which it is guided by the semi-cylindrical front portion of the apron 45.

For the purpose of supporting and guiding the advanced end or written portion of the web, a sheet metal paper table 52 is secured above the guide 49 and is extended to the periphery of the platen in rear of the printing point, see Fig. 8. The apron 45, guide 49, and table 52 may be secured in any
 35 suitable manner, one convenient mode being that shown in detail in Fig. 4 wherein a screw 53 is passed through the table, guide and apron and into the frame member 19, a spacing member 54 being interposed between
 40 the guide and apron and retained by the screw.

The paper roll 41 is protected by a sheet metal roll cover 55 hinged upon the transverse frame bar 18, as shown in Fig. 5, and having fingers 56 which rest upon the rear edge of the apron 45. The fingers 56 not only serve to hold the front edge of the roll cover 55 in position, but constitute lateral guides for the web which passes upwardly
 50 from the roll between the front edge of the cover 55 and the rear edge of the apron 45. If desired, additional lateral guides for the web may be provided in the form of flanges 57 extended along the opposite sides of the
 55 apron 45. It will be noted that the cover 55 constitutes a rearward extension of the apron 45 so that as the advanced end of the paper web moves rearwardly from the paper table 52 it will be supported by the
 60 apron and guided over the paper roll by the cover 55 until it drops from the rear end of the roll cover and is received within a suitable receptacle located below the rear end of the platen frame.

65 Disposed along the platen 20 adjacent to

but in rear of the line of writing or printing point is a scale bar 58 carried by swinging arms 59 pivotally connected at their rear ends to the frame members 10 and 11, as indicated at 60. A stop 61 screwed into one side of the frame engages one of the arms 59 of the scale bar whereby the latter is held by gravity close to the platen to aid in holding the paper smooth at the printing point without, however, imposing the weight of the scale bar upon the web. This scale bar ordinarily occupies the normal position shown in the drawings, but may be easily thrown back from the platen to facilitate the initial threading of the web.

70 The line spacing mechanism by means of which the platen is rotated step by step in a manner well understood in the art includes a line spacing lever 62 mounted to swing from the shaft 28 and urged in one direction by a spring 63. At the front end of the lever is formed a finger piece 64 and at its rear end is a laterally disposed pin 65 received within a slot 66 in a pawl carrier 67. The pawl carrier is in the form of an 75 arm having a line spacing pawl 68 at its front end and loosely swung at its rear end from the platen spindle 21, the carrier 67 being provided with a slot 69 for the reception of the spindle. At a point below the 80 slot 69 the carrier 67 is secured to the front end of a retracting spring 70 housed in a recess 71 in the adjacent side member of the frame and having its rear end secured to a fixed part as for instance a screw 72. 85 The joint actions of the springs 63 and 70 normally retain the line space lever 62 and the pawl carrier 67 in the position shown in Fig. 9, it being noted that the pawl 68 while contiguous to the teeth of the ratchet 23 is 90 normally entirely disengaged from said ratchet to permit the platen to be freely turned by the manipulation of the thumb wheels 22. When it is desired to line space 95 the writing on the web the operator depresses the front end of the lever 62 toward the dotted position indicated in Fig. 9. This movement of the lever causes the pin 65 to describe an arc which causes it to elevate the front end of the pawl carrier 67 100 and at the same time recede sufficiently to enable the spring 70 to draw the beak of the pawl 68 into engagement with a tooth of the ratchet 23. Continued movement of the 105 lever 62 will cause the pin 65 to elevate the pawl carrier 67 and thus advance the ratchet and rotate the platen, the arcuate path traversed by the pawl 68 as it moves with the periphery of the wheel 23 being accommodated by the slot 69 in the pawl carrier 67. 110 The upward movement of the pawl carrier 67 and consequently the degree of rotary movement imparted to the platen is limited by a variable line-space stop member 73 115 having stop faces *a*, *b*, *c*, disposed in gradu- 120
 125
 130

ated arrangement. In order to provide for the shifting of the stop member 73 in order to bring any desired stop into position to coact with the pawl carrier 67, said member 73 is movable with a slide 74 preferably integral with the stop member and movable in a guideway 75 formed in the adjacent side member of the frame. At its front end the slide 74 is provided with a finger piece 76 by means of which it may be readily manipulated and its retention in each of its several positions is effected by means of a spring-urged detent 77 engaging notches 78 in the bottom wall of the guideway 75. A headed screw 79 screwed into the side of the frame serves to prevent lateral displacement of the slide 74.

By reference to Fig. 9 it will be seen that when narrow spacing is desired the variable stop 73 is moved to its innermost position so as to arrest the pawl carrier 67 after comparatively slight rotary movement of the platen. If intermediate spacing is desired the member 73 is drawn out, as shown in Fig. 10, to permit the pawl carrier to have further movement limited by the engagement thereof with the intermediate stop face *b* and when wide spacing is desired the stop member is drawn out to the position indicated in Fig. 11 so as to permit a still greater movement of the carrier 67 limited by the engagement thereof with the third and last stop face *c*. It is obvious, however, that if a greater variety of spacing is required, the number of line space stops or stop faces may be increased.

It is thought that from the foregoing, the described construction and arrangement of parts will be readily comprehended, but while the present embodiment of the invention is believed to be preferable, I expressly reserve the right to effect such variations of the illustrated structure as may come fairly within the scope of the protection prayed.

What I claim is:

1. The combination with a supporting frame and a printing machine movably mounted thereon, of a platen mounted in the supporting frame adjacent to its front end, means for mounting a paper roll in rear of said platen, an apron mounted in the supporting frame and arranged to lead a paper web from the roll to the platen, a paper guide disposed substantially parallel to the apron to form a guideway for the web, and a horizontal paper support located in rear of the platen to support that portion of the web extended rearwardly from said member.

2. The combination with a supporting frame and a printing machine movable thereon, of a rotary platen mounted in the supporting frame adjacent to its front end, feed rolls and line spacing mechanism asso-

ciated with said platen, an apron located in rear of the platen and having a guideway at its front end for a paper web, and a horizontal paper support located in rear of the platen.

3. The combination with a supporting frame and a printing machine movable thereon, of a rotary platen mounted in said frame adjacent to its front end, means for mounting a paper roll in said frame in rear of the platen, a web supporting apron intermediate of the paper roll and platen, and a roll cover constituting a continuation of the apron and arranged to guide the rearwardly advancing end of the paper web over the roll.

4. The combination with a supporting frame and a printing machine movable thereon, of a rotary platen mounted in the supporting frame adjacent to its front end, feed rolls and line spacing mechanism associated with said platen, means for mounting a paper roll in the supporting frame in rear of the rotary member, an apron extended between the paper roll and the platen and provided with longitudinally disposed lateral paper guides and also having a guideway at its front end arranged to lead the web around the under side of the platen, and a horizontal paper support located above the apron and in rear of the platen.

5. In a mechanism of the character described, the combination with a frame, of paper feeding mechanism including a rotary platen mounted in the frame, two series of feed rolls coacting with said platen, a pair of rock shafts, a series of roll frames mounted to swing from each shaft, springs for urging the roll frames toward the platen, projections extended from each rock shaft and disposed to engage and swing the roll frames when the shafts are rocked, an arm extended from each shaft, a link connecting the arms, and a lever provided with a notched end coacting with one of said arms to rock the shafts for the purpose of withdrawing the feed rolls from the platen and to retain said shafts in the positions to which they are rocked.

6. The combination with a stationary frame, of a rotary platen mounted therein, means for mounting a paper feed roll in rear of the platen, paper guiding means intermediate of the platen and roll mounting, means for supporting that portion of the paper which has been extended back from the platen, and a printing machine normally disposed over the platen but movable on the stationary frame to a position away from the platen.

7. In a mechanism of the character described, the combination with a frame, of paper feeding mechanism including a platen mounted in the frame, feed rolls coacting with the platen, a rock shaft, a series of

spring urged roll frames mounted to swing from said shaft, springs urging the roll frames toward the platen, projections extended from the rock shaft to engage and 5 swing the roll frames, an arm extended from the shaft, and a lever having a notched end coacting with said arm to rock the shaft for the purpose of withdrawing the feed rolls

from the platen and to retain said shaft in the position to which it is rocked. 10

In testimony whereof I affix my signature in presence of two witnesses.

OLAF O. MARTIN.
